(57) **CLAIM**

The ornamental design for a projection screen, as shown and described.

DESCRIPTION

FIG. 1 is a front perspective view of a projection screen design showing my new design.

FIG. 2 is a rear perspective view of a projection screen.

FIG. 3 is a front view of a projection screen.

FIG. 4 is a rear view of a projection screen.

FIG. 5 is a left side view of a projection screen, shown enlarged in scale.

FIG. 6 is a right side view of a projection screen, shown enlarged in scale.

FIG. 7 is a top view of a projection screen.

FIG. 8 is a bottom view of a projection screen.

FIG. 9 is an enlarged view of the end of the bracket of the projection screen taken from the circle part in FIG. 4.

FIG. 10 is an enlarged view of the middle of the bracket of the projection screen taken from the circle part in FIG. 4.

FIG. 11 is an enlarged view of the projection screen taken from the circle part in FIG. 5.

FIG. 12 is an enlarged view of the projection screen taken from the circle part in FIG. 7; and,

FIG. 13 is an enlarged view of the projection screen taken from the circle part in FIG. 8.

Any shading and cross-hatching are not features of the design but are utilized to illustrate the surface contours of the projection screen design in the drawings.
